UNITED STATES PATENT OFFICE.

HORACE D. BERNARD, OF BEAUMONT, TEXAS.

VALVE FOR OIL-WELLS.

No. 799,967.

Specification of Letters Patent.

Patented Sept. 19, 1905.

Application filed May 18, 1905. Serial No. 260,964.

To all whom it may concern:

Be it known that I, HORACE D. BERNARD, a citizen of the United States, and a resident of Beaumont, in the county of Jefferson and 5 State of Texas, have invented a new and Improved Valve for Oil-Wells, of which the following is a full, clear, and exact description.

This invention relates to valves for oil-wells; and its object is to provide a valve 10 which is adapted to form a good joint at the stem of the drill and which affords means for controlling the flow of the oil during the drilling operation and thereafter.

The invention consists in the construction 15 and combination of parts to be more fully described hereinafter and definitely set forth in the claims.

Reference is to be had to the accompanying drawings, forming a part of this specification, in which similar characters of reference indicate corresponding parts in all the figures.

Figure 1 is a cross-section through a derrick-floor and showing how my valve is applied in practice, the valve and its contiguous parts being shown in elevation and broken away, as will appear. Fig. 2 is a vertical section through the valve-body and illustrating the manner in which the valve 25 operates to shut off communication from the well. In this view certain parts are broken away, as will appear. Fig. 3 is a section taken substantially upon the line 3 3 of Fig. 4 and looking upwardly. Fig. 4 is a vertical central section taken through the valve, its contiguous parts being represented as broken away. Fig. 5 is a transverse vertical section taken upon the line 5 5 of Fig. 4, and Fig. 6 35 is a transverse vertical section taken upon the line 6 6 of Fig. 4.

Referring more particularly to the parts, 1 represents the oil tube or casing, which is sunk in the well in the usual manner, terminating above in a flange 2, to which my valve 45 3 attaches. The body 4 of this valve has the general form of a cross connection for piping, being open above and below and on each side. It presents a flange or hub 5 below, which is bolted to the flange 2, as indicated, and is formed with hubs 6 at the sides, to which bonnets 7 and 8 are attached, 50 projecting horizontally in each direction, as indicated. In practice this valve is mounted, as shown in Fig. 1, just beneath the floor 55 of the derrick 9. The drill-stem 10 passes vertically upward in the casing 1 and out

through the upper side of the valve-body, as indicated. The interior construction of the valve is most clearly illustrated in Figs. 4 to 6.

The bonnet 7 is represented in section in Fig. 4. Its lower portion is substantially rectangular or square in section, and its upper portion is formed into a crown or dome 11, having the outline of a cylinder. At the 65 bottom and on the sides longitudinally-disposed grooves 12 are formed in the bonnet-wall, and in these grooves tongues 13 lie, which are formed upon and project laterally from the main valve 14. The body of this 70 valve conforms, substantially as indicated, to the cross-section of the bonnet, and the tongues 13 are formed with longitudinal grooves which receive hydraulic packing 15. The inner extremity of the main valve 14 is 75 formed with a concave or semicylindrical face 16, as indicated most clearly in Figs. 2 and 3. The radius of curvature of this face will depend upon the diameter of the drill-stem 10 and will be such as to enable this 80 face of the valve to seat closely against the stem, as indicated in Fig. 4. In this face 16 a groove is formed containing a packing-strip 17.

The left side of the body 4 of the valve, to 85 which the bonnet 7 is attached, has the same general form as the bonnet, so that the bores of the bonnet and body substantially coincide. From this arrangement the interiors of these parts constitute a continuous guide 90 for the main valve 14. The said valve may be advanced or withdrawn by means of a threaded valve-stem 18, which is rotatably mounted in a head or cover 19 of the bonnet in a manner which will be described more 95 fully hereinafter.

As indicated most clearly in Fig. 3, the bottom 20 of the main valve 14 projects forwardly, so as to present a rounded nose 21, in which nose one of the aforesaid packing-strips 17 lies, as indicated. Opposite this nose 21 the lower portion of the body 1 of the valve is formed with a rounded face 22, constituting a seat against which the nose of the valve may be pressed, as indicated in Fig. 2. 100 This of course can only be done after the drill-stem 10 is removed from the interior of the body. When the main valve 14 is used in this manner, it constitutes a gate-valve, affording means for closing completely 105 communication between the interior of the valve-body and the casing 1.

The bonnet 8 is of cylindrical form and provided with a horizontally-transverse web 23, which divides it into an upper chamber 24 and a lower chamber 25. At the bottom 5 of the upper chamber 24 oppositely-disposed grooves 26 are formed in the wall of the bonnet, and these grooves receive tongues 27, which project laterally from a valve 28. This valve 28, as indicated in Fig. 6, has a 10 cross-section which corresponds to the outline of the bonnet, and its forward extremity normally projects into the interior of the body 1 and is provided with a concave or semicylindrical face 29, similar to the face 15 16 described in connection with the valve 14. In its lower portion and preferably opposite to the packing-strip 17 a strip 30 is received in the face 29, as indicated. This valve may be advanced or withdrawn by 20 means of a threaded valve-stem 31, which is rotatably mounted in the bonnet-cover 32.

In the lower side of the bonnet 8 is provided a hub 33, to which an elbow 34 is attached communicating with an overflow-pipe 35. The opening through this hub may 25 be closed at will by means of an auxiliary gate-valve 36. The form of this valve is clearly shown in Fig. 6. It conforms substantially to the cross-section of the valve-chamber 25. This valve may be advanced or withdrawn by means of a threaded stem 37, which is also rotatably mounted in the cover 32. The rear extremities of the valves 28, 36, and 14 are preferably packed with 30 packing-strips 38 in double rows, as shown. 35

The manner of rotatably mounting the valve-stems 18, 31, and 37 in the covers 19 and 32 will now be described. These stems are provided with reduced necks 39 at the 40 covers, and the covers are recessed, as indicated, so as to receive collars 40, said collars being located at the reduced necks and affording means for locking the stems against longitudinal movement. The collars are retained in place by plates 41, secured to the under sides of the covers, as shown, said plates having openings through which the bodies of the stems pass, as indicated. The upper neck or hub 42 of the body 1 is internally threaded, so as to receive a plug 43, as 45 indicated in Fig. 2. This plug is for the purpose of closing communication from the body 4 to the casing 1 without using the main valve 14 for this purpose. In order to do 50 this, the main valve would be withdrawn, so as to permit the plug 43 to be screwed down into the interior of the body, and the upper portion of the inlet-neck 44 of the body 4 is slightly bored conically, as at 45, so as to 55 form a seat for the extremity of the plug. In order to make the retaining-grooves for the packing more efficient in holding the same, the walls thereof are preferably formed with inwardly-projecting shoulders 46, which grip 60 the body of the packing, as will be readily 65

understood, so as to prevent the same from being pulled outwardly. The outer faces of these shoulders incline inwardly, enabling the packing to be inserted, while the inner faces are abrupt, so as to oppose the withdrawal of the packing. 70

The operation of the valve is now to be described.

Under normal conditions when the drilling operation is progressing the stem 10 will pass 75 downwardly through the body of the valve, as indicated in Figs. 1 and 4. The valves 14 and 28 will be advanced, so that their forward faces abut against the sides of the drilling-stem and form a tight joint thereabout, so as 80 to prevent the upward flow of gas, oil, or sand. As the drilling operation progresses the overflow of oil, sand, or gas is controlled by means of the gate-valve 36, which may open communication when desired with the 85 overflow-pipe 35. When the drilling-stem 10 is removed, the main valve 14 may be advanced, as indicated in Fig. 2, so as to close the opening from the casing 1 to the body 4. The entire bonnet 8 may be removed, if desired, after the well has been brought in and a pipe-line connected directly in the position which the bonnet occupied. If the well is to be permanently closed or closed for a long period, both bonnets 7 and 8 will be removed 90 and the plug 43 will be screwed down, so as to seat itself in the body and cut off communication with the casing. The valve-stems would be operated by hand-wheels 47 and would project to a point beyond the end of 95 the derrick-floor, enabling these hand-wheels to be conveniently reached.

With the valves 14 and 28 in the position shown in Fig. 4 they constitute a packing for the joint of the stem with the valve, their forward faces preferably abutting, as indicated in Fig. 4. In this way the oil or other material coming up the pipe is prevented from passing up through the body, and, further, attention is called to the fact that when the drill-stem 10 has been removed the valve 14 then operates in a new capacity as a simple gate-valve, shutting off communication between the casing and the lower portion of the body. 110 115

Having thus described my invention, I claim as new and desire to secure by Letters Patent—

1. In a valve of the class described, in combination, a body through which a drill-stem may pass, oppositely-disposed valves having concave faces adapted to abut against the sides of said stem, one of said valves constituting a gate-valve adapted to shut off communication at the lower side of said body, the lower portion of said body being formed into a seat coöperating therewith. 120 125

2. In a valve of the class described, in combination, a body adapted to have a drill-stem pass upwardly therethrough, a main 130

valve having a concave face adapted to abut the side of said stem, a second valve having a concave face adapted to abut the side of said stem opposite to said first valve, the lower 5 side of said main valve presenting a substantially flat face constituting a gate, and means for advancing said main valve to shut off the lower portion of said body.

3. In a valve of the class described, in 10 combination, a body through which a drill-stem may pass upwardly, a pair of oppositely-disposed packing-valves coöperating to grasp said stem therebetween, said valve having an overflow-outlet, and a third valve controlling 15 said outlet.

4. A valve of the class described, in combination, a body, a pair of oppositely-disposed packing-valves adapted to grasp the stem passing up through said body, a bonnet 20 attached to said body and having an overflow-outlet leading therefrom which may communicate with the interior of said body, and a third valve controlling said outlet.

5. In a valve of the class described in 25 combination, a body adapted to have a drill-stem pass upwardly therefrom, a bonnet attached to said body, a packing-valve mounted in a portion of said bonnet and affording means for packing a portion of said stem, 30 said bonnet having an overflow-outlet, and a second valve mounted in said bonnet and controlling said overflow-outlet.

6. In a valve of the class described, in 35 combination, a body adapted to have a drill-stem pass upwardly therethrough, a bonnet attached at the side of said body and having an upper valve-chamber and a lower valve-chamber, a packing-valve mounted in said upper chamber and having a concave forward 40 face adapted to pack a portion of said

stem, said lower valve-chamber having an outlet therefrom, and a second valve mounted in said lower valve-chamber and controlling said outlet.

7. In a valve of the class described, in 45 combination, a body adapted to have a drill-stem pass upwardly therethrough, bonnets attached on opposite sides of said body, a main valve in one of said bonnets and having a concave forward face adapted to abut 50 against said stem, a packing-valve opposite said first valve, and mounted on the other bonnet, said packing-valve having a concave face adapted to abut said stem, said other bonnet having an overflow-outlet therefrom, 55 and a third valve mounted in said bonnet and controlling said outlet.

8. In a valve of the class described, in combination, a body adapted to have a drill-stem pass upwardly therethrough, a bonnet 60 attached to said body of substantially cylindrical form and having a transverse horizontal web therein, dividing the interior of said bonnet into an upper valve-chamber and a lower valve-chamber, a packing-valve 65 mounted in said upper valve-chamber and having a concave forward face adapted to engage said drill-stem to pack a portion of the same, said lower valve-chamber having an overflow-outlet therefrom, and a second 70 valve mounted in said lower valve-chamber and adapted to close said opening.

In testimony whereof I have signed my name to this specification in the presence of two subscribing witnesses.

HORACE D. BERNARD.
